George B. Ross, Inventor.
By James Daugler, Attorney.

UNITED STATES PATENT OFFICE.

GEORGE B. ROSS, OF BUFFALO, NEW YORK.

COMBINED SYRINGE AND MEDICINE-CASE.

SPECIFICATION forming part of Letters Patent No. 400,491, dated April 2, 1889.

Application filed December 29, 1888. Serial No. 294,914. (No model.)

To all whom it may concern:

Be it known that I, GEORGE B. ROSS, a citizen of the United States, residing in Buffalo, in the county of Erie and State of New York, 5 have invented certain new and useful Improvements in Pocket Medicine-Cases, of which the following is a specification.

The object of my invention is to provide a convenient combined pocket-case and syringe 10 for carrying medicine, and having also within it the means for mixing the medicine with liquid and administering it when required, all of which will be fully and clearly hereinafter described and claimed, reference being had to 15 the accompanying drawings, in which—

Figure 1 is a side elevation of the device. Fig. 2 is a vertical longitudinal central section through the same. Fig. 3 is a vertical longitudinal central section through the 20 syringe separate from the case, showing it partly opened or the piston partly withdrawn, and a small pellet or tablet of medicine in position to be shaken up with water or other liquid and dissolved. Fig. 4 is a cross-section 25 through line *a b*, Fig. 1.

In said drawings, 1 represents the outer case. 2 is a reduced portion adapted to receive the cover 3, which is fitted nicely, so as to leave all of the same diameter. This outer 30 case is preferably made of hard rubber or celluloid; but it may be made of glass, metal, or other suitable material. In the lower portion, near the end, is a ring or washer, 4, of some elastic or soft substance, such as cork, 35 felt, or other similar material. Its object is to prevent the nozzle of the syringe from being pushed down too far into the case. It also tends to keep the end of the syringe in a central position within the case, and also protects the end of the nozzle, and prevents it 40 from being broken.

If desired, the case 3 may be adapted to screw on the reduced portion 2 instead of being slipped on, as shown.

45 The body or outer syringe-case, 5, is preferably made of glass; but it may be composed of any well-known material suitable for the purpose. It is provided with the usual reduced portion or nozzle, 6, and at the top is 50 an outwardly-projecting flange, 7, adapted to rest against the top edge of the reduced por-

tion 2 of the outer case, to prevent it from being pushed in too far, and thereby injure the nozzle 6. The plunger or piston is a hollow receptacle, 8, having near the lower end a reduced portion, 9, to receive a suitable packing, 10, of cotton- or other soft packing material, to insure a water-tight fit within the case 5. At the opposite end of the plunger is a ring or projecting rib, 11. Against this rib is 55 a thin soft piece of felt, 12, or other similar soft material, surrounding the plunger and extending a short distance down from the rib. Its object is to keep the plunger central within the case 5, and prevent it from going 60 too far into the case. At the top of the plunger is another rib or flange, 13, and an opening adapted to receive a stopper or cork, 14. This plunger, being a hollow receptacle, holds the medicine, preferably in the form of small 65 soluble pellets or tablets 15, as being the most convenient to insure a proper dose of the medicine being used; but the medicine may be put up in any form desired.

The operation of the device is as follows: 75 When one or more pellets or tablets are sufficient for a dose, the case 1 is opened, the syringe taken out, and the plunger removed. A single one or more tablets are then taken out from the receptacle, by removing the stopper 80 14, and put into the case 5, as shown at 16, Fig. 3. The plunger 8 (to which the stopper 14 has been returned) is now inserted, and a sufficient amount of water (or other liquid) drawn in, and by placing the finger over the 85 end of the nozzle it may be shaken until the pellet or pellets are dissolved, after which the medicated liquid may be administered in any way desired.

If required, the plunger may be provided 90 with a cover adapted to screw on; or it may be made similar to the cover shown on the outer case.

I claim as my invention—

1. In a pocket medicine-case, the combination of an outer case, a syringe-body having a reduced end or nozzle adapted to fit the holding-case, a hollow cylindrical plunger for holding the medicine and operating the syringe, and having an opening at the outer end provided with a stopper for closing it, and a packing of soft material for insuring a tight 95 100

joint for the piston within the body of the syringe, substantially as described.

2. The combination of the holding-case 1, provided with a cover and an elastic washer, 4, a syringe-case, 5, a hollow plunger or piston, 8, provided with a packing, 10, for holding the medicine and operating the syringe,

and a stopper for closing the open end of the plunger, substantially as described.

GEORGE B. ROSS.
